(57) **CLAIM**

The ornamental design for a vertical bifold cell phone wallet,
as shown and described.

DESCRIPTION

FIG. 1 is a perspective view of a vertical bifold cell phone
wallet with interior slot pockets according to one embodiment
showing my new design;
FIG. 2 is a front view thereof;
FIG. 3 is a rear view thereof;
FIG. 4 is a left side view thereof;
FIG. 5 is a right side view thereof;
FIG. 6 is a top view thereof;
FIG. 7 is a bottom view thereof;
FIG. 8 is a perspective view of the vertical bifold cell phone
wallet with interior slot pockets in an open condition;

FIG. 9 is a front view thereof;
FIG. 10 is a rear view thereof;
FIG. 11 is a left side view thereof;
FIG. 12 is a right side view thereof;
FIG. 13 is a top view thereof;
FIG. 14 is a bottom view thereof;
FIG. 17 is a perspective view of a vertical bifold cell phone
wallet with an exterior slot pocket and interior slot pockets
according to another embodiment showing my new design;
FIG. 18 is front view thereof;
FIG. 3 is a rear view thereof;
FIG. 4 is a left side view thereof;
FIG. 5 is a right side view thereof;
FIG. 6 is a top view thereof;
FIG. 7 is a bottom view thereof;
FIG. 19 is a perspective view of the vertical bifold cell phone
wallet with an exterior slot pocket and interior slot pockets in
an open condition;
FIG. 20 is a front view thereof;
FIG. 21 is a rear view thereof;
FIG. 11 is a left side view thereof;
FIG. 12 is a right side view thereof;
FIG. 13 is a top view thereof; and,
FIG. 14 is a bottom view thereof.

The broken lines showing portions of a wallet are for the
purposes of illustrating environment and form no part of the
claimed design.

(57) CLAIM

The ornamental design for a vertical bifold cell phone wallet,
as shown and described.

DESCRIPTION

FIG. 1 is a perspective view of a vertical bifold cell phone
wallet with interior slot pockets according to one embodiment
showing my new design;
FIG. 2 is a front view thereof;
FIG. 3 is a rear view thereof;
FIG. 4 is a left side view thereof;
FIG. 5 is a right side view thereof;
FIG. 6 is a top view thereof;
FIG. 7 is a bottom view thereof;
FIG. 8 is a perspective view of the vertical bifold cell phone
wallet with interior slot pockets in an open condition;

FIG. 9 is a front view thereof;
FIG. 10 is a rear view thereof;
FIG. 11 is a left side view thereof;
FIG. 12 is a right side view thereof;
FIG. 13 is a top view thereof;
FIG. 14 is a bottom view thereof;
FIG. 17 is a perspective view of a vertical bifold cell phone
wallet with an exterior slot pocket and interior slot pockets
according to another embodiment showing my new design;
FIG. 18 is front view thereof;
FIG. 3 is a rear view thereof;
FIG. 4 is a left side view thereof;
FIG. 5 is a right side view thereof;
FIG. 6 is a top view thereof;
FIG. 7 is a bottom view thereof;
FIG. 19 is a perspective view of the vertical bifold cell phone
wallet with an exterior slot pocket and interior slot pockets in
an open condition;
FIG. 20 is a front view thereof;
FIG. 21 is a rear view thereof;
FIG. 11 is a left side view thereof;
FIG. 12 is a right side view thereof;
FIG. 13 is a top view thereof; and
FIG. 14 is a bottom view thereof.
The broken lines showing portions of a wallet are for the
purposes of illustrating environment and form no part of the
claimed design.
